UNITED STATES PATENT OFFICE.

HARRISON E. HERRICK, OF MERRIMAC, NEW HAMPSHIRE.

SPRING-BACK FOR VEHICLE-SEATS.

SPECIFICATION forming part of Letters Patent No. 503,319, dated August 15, 1893.

Application filed December 24, 1892. Serial No. 456,262. (No model.)

To all whom it may concern:

Be it known that I, HARRISON E. HERRICK, of Merrimac, in the county of Hillsborough and State of New Hampshire, have invented 5 certain new and useful Improvements in Spring Attachments for Carriage-Backs, of which the following is a specification.

My invention has relation to the backs of seats of wagons and other vehicles; and it has 10 for its object the provision of means whereby the back of the seat may be made to yield when subjected to undue pressure thereagainst by the occupant, as when the wheels of the vehicle strike a water-bar or pitch-hole 15 in the road, or when the horse starts quickly or springs forward suddenly as is sometimes the case when touched with a whip or urged by the manipulation of the reins or otherwise.

To these ends the invention consists of the 20 improvements which I will now proceed to describe and claim.

Reference is to be had to the annexed drawings, and to the letters marked thereon, the same letters designating the same parts or features, as the case may be, wherever they occur.

Of the drawings—Figure 1 is a front view of my improved seat back free from upholstering. Fig. 2 is an end view of the same, the upholstering being represented in dotted 30 lines.

In the drawings *a* designates the seat.

b is the base or support and *d* is the back. The latter without upholstering may consist 35 of a plain board or piece of any desired width. *c* is an oscillatory rod arranged in suitable bearings *d* secured to the back *b'*. The rod *c* is arranged longitudinally of the seat back, and the outer end of said rod, projecting beyond the end of the back is formed into or 40 provided with a crank *e*, to the free end of which is pivoted the rear end of the seat-arm *f*, the forward end of said arm being pivoted upon a boss or projection *g* of the seat-handle *h*.

i designates an arm or brace secured at its 45 upper end to the back of the seat and pivoted at its lower end as at *j* upon a bracket *k* secured to the seat rail *l*.

m is a spring coiled around the oscillatory rod *c* and having one end secured to the bearing *b*, or, it might be, the seat back, and the other end attached to the collar *n* which, in turn, is rigidly secured to the oscillatory rod. The said spring operates torsionally upon the said rod, and with a tendency to move the 55 back of the seat forward, as will be readily understood without further description. The collar *n* is provided with a projection *o* serving as a stop, which is adapted when the back of the seat is moved forward by the operation 60 of the said spring to come into contact with a stop *p* formed upon one of the bearings *d*, and so limit the extent of the forward movement of the seat back.

The forward face of the seat back may be 65 cushioned and upholstered, as at *q*, in any suitable way.

With this invention a seat-back for vehicles is provided which is soft and yielding in character and which obviates all harmful and 70 disagreeable jar and jolt to the occupant of the vehicle, arising from any cause.

It will be observed that the contrivance is very simple in construction, easy of manufacture and ready of application. It will also 75 be noted that changes may be made in the form and arrangement of parts comprising the invention, to adapt it to meet special circumstances or tastes, without departing from the nature or spirit of the invention. 80

I claim—

A back for vehicle seats comprising in its construction pivotal supports, a rock rod provided with a crank having bearings in the back, a spring for exerting torsional strain 85 upon said rod, and the seat arm pivotally connected with said crank and the seat, as set forth.

In testimony whereof I have signed my name to this specification, in the presence of 90 two subscribing witnesses, this 20th day of August, A. D. 1892.

HARRISON E. HERRICK.

Witnesses:

R. P. ELLIOTT,
GEORGE A. UNDERHILL.
